[57] CLAIM

The ornamental design for a cigar ventilator, as shown
and described.

DESCRIPTION

FIG. 1 is a perspective view of a cigar ventilator showing
our new design;

FIG. 2 is a side elevational view thereof, the opposite
side, top plan and bottom plan views having the same
appearance;

FIG. 3 is a left end elevational view thereof;

FIG. 4 is a right end elevational view thereof; and

FIG. 5 is a side elevational view of a cigar ventilator
showing our new design in the actuated position.
